UNITED STATES PATENT OFFICE.

JOHN NEGRESCO, OF CHICAGO, ILLINOIS.

WASHING-MACHINE.

1,360,009.

Specification of Letters Patent. Patented Nov. 23, 1920.

Application filed November 28, 1919. Serial No. 341,103.

To all whom it may concern:

Be it known that I, JOHN NEGRESCO, a citizen of the United States, and a resident of Chicago, in the county of Cook and State of Illinois, have invented certain new and useful Improvements in Washing-Machines, of which the following is a specification.

My invention relates to improvements in washing machines, and more particularly to the class of washing machines fully set forth in the prior application filed by me in the United States Patent Office on the 4th day of October, 1918, and bearing Serial No. 256,784.

The present invention pertains more especially to a combination of members which serve as a safety device to prevent injury to the clothes and water-containing receptacle, by the operation of the gas burner or other heating element provided beneath the tub for heating the water therein during the period when the receptacle is empty after the discharge of the water therefrom.

The features embodying my invention are hereinafter set forth in detail and fully disclosed in the accompanying drawings, in which—

Figure 1 is a view in elevation of the washing machine showing the parts embodying the invention, and

Fig. 2 is a detail view in section, taken on line 2, 2 of Fig. 1.

In order that a thorough understanding may be had of the washing machine to which this invention relates, the principal parts and mode of operation will be set forth. The machine comprises in general a cylindric-shaped tub 1 mounted in vertical position upon legs 2, 2, said tub having a removable cover 3 extending over substantially one-half the top thereof, the remaining portion of the top being permanently closed by a wall 4 upon which is mounted certain operating members hereinafter to be described. Within the receptacle 1 is a cylindric-shaped basket 5, the same being secured to a frame 6, which in turn is mounted upon a vertically arranged hollow shaft 7. The shaft 7 is journaled within a bearing box 8 mounted in the top wall 4 of the receptacle, there being keyed to the upper end of the shaft 7 a bevel gear wheel 9. The basket 5 is also journaled upon the bot-

tom of the receptacle by means of a suitable centrally disposed journal.

Rigidly mounted upon the top wall 4 of the receptacle is a supporting frame 10 in which is journaled a horizontal shaft 11, having at one end a bevel gear wheel 12 meshing with the bevel gear wheel 9 of the shaft 7, and at its opposite end is keyed a pulley 13. Mounted on the horizontal shaft 11 and adapted to rotate loosely thereon is a worm shaft 14, said worm shaft having fixed thereto a pulley 15. The worm of the worm shaft 14 meshes with a worm-wheel 16 immediately below, said worm wheel being keyed to a transverse shaft 17 having operative connection with a rocker arm 18 by means of an intermediate crank and slot connection (not shown). Mounted in a vertically arranged journal bearing 19 integral with the frame 10 is a vertical shaft 20 adapted to extend through the hollow shaft 7 and into the tub 1. The shaft 20 is driven with a reciprocating movement by means of the rocker arm 18 which is connected to the shaft 20 by means of a fixed collar 21 mounted on said shaft, there being further mechanism adapted to transmit a limited rotative movement to the shaft 20 during each of its strokes in a vertical direction. Secured to the lower end of the shaft 20 are radially extending arms 22, 22, there being fixed to the ends of said arms downwardly opening cup members 23, which by reason of their function are ordinarily known as vacuum cups.

In the operation of the machine the parts are so arranged that the rotation of the basket is effected during the period that the vertical shaft 20 is stationary, and vice versa, the vertical reciprocating movement of the vertical shaft 20 is carried on during the period that the basket 5 is at rest, it being understood that the cleansing of the clothes is accomplished by agitating the same by means of the reciprocating movement of the vacuum cups in contact therewith, the cleansing process being followed by the discharge of the water from the receptacle 1 and subsequently revolving the basket for the purpose of removing the water from the clothes by centrifugal force. The shifting from one operation to the other is accomplished by shifting the drive belt 26 from the pulley 15 to the pulley 13, and

vice versa, said belt 26 being carried by a pulley driven by a suitable motor mounted at the base of the machine. The belt shifting device consists of an endwise movable bar 28 which engages the belt at its outer end and a shifting lever 29 being provided with a toothed sector 29^a at its lower end, which meshes with a rack 28^a formed in the shifting bar 28. Intermediate the pulleys 10 13 and 15 is preferably provided an idler pulley 30 to which the belt may be shifted if it is desired to stop the operation of the machine without shutting off the motor.

For the purpose of heating the water 15 within the receptacle or tub 1 there is provided a gas burner 31 located beneath and adjacent to the bottom wall of the tub. The burner 31 may be of any suitable type and have connected therewith a pipe 32 for supplying gas to the burner. In the pipe 32 and adjacent to the burner is a valve 33 provided with a valve handle 34 preferably extending in a direction to the left, as shown in Fig. 1 of the drawing, and arranged to 20 occupy a horizontal position when the gas valve is closed.

Adjacent to the burner 31 of the heating apparatus is the water discharge passage 35 which communicates with the tub 1 and 25 serves as a means for drawing off or discharging the water from the tub after the clothes have been cleaned and prior to the drying operation. It is to be pointed out that it is more desirable and economical to 30 use the same water for several qualities of clothes, therefore the water is discharged into a separate receptacle 36 immediately below the tub 1. The passage 35 consists of a pipe and a discharge fitting 37 having a 35 valve 37^a therein, said valve being provided with an operating lever 38 adapted to occupy a horizontal position when the valve is open and to extend in the direction of the heating apparatus. The relation of the gas valve 40 handle 34 and the water discharge valve lever 38 is clearly shown in Fig. 2, said members being substantially parallel to each other, the lever 38 overlapping said valve handle 34 and in contact therewith through 45 the medium of a lug or projection 39 formed at the end of the lever 38.

As before suggested, the gas valve 33 is in closed position when its valve handle 34 is in horizontal position, whereas the water 50 discharge valve is open when its operating lever is in horizontal position and in contact with the valve handle 34. It is evident that so long as the discharge valve is open the gas will be shut off, hence the person will 55 not inadvertently light the burner so long as there is no water in the tub. Similarly if the burner is lighted and a quantity of water is within the tub, both members 34 and 38 will be in raised position and in the

act of discharging the water from the tub 65 the valve lever 38 will be moved downwardly to open position and in so doing will come in contact with the gas valve handle 34 and automatically close the same, thus extinguishing the burner.

This arrangement provides a simple yet exceedingly desirable safety device which insures the protection of the tub and contents by making it impossible for the burner to remain lighted under the tub when there 70 75 is no water therein.

Although I have described and illustrated the preferred embodiment of the invention, it is manifest that the same may be considerably modified without departing from the 80 spirit of the invention, therefore I do not wish to be limited except in so far as I have expressly defined the invention in the appended claims.

I claim as my invention :

1. In a washing machine, the combination 85 of a tub provided with a liquid discharge valve and a valve operating member, a heating element associated with said tub, and a heating medium controlling member positioned to be engaged by said liquid valve operating member to automatically shut off said heating element when said liquid discharge valve is opened.

2. In a washing machine, the combination 90 of a tub provided with a liquid discharge passage, a valve and a valve operating member, a heating element and heating medium controlling member associated with said tub, said controlling member having operative 100 connection with said liquid valve operating member to effect the shutting off of said heating element when said liquid valve member is moved into open position.

3. In a washing machine, the combination 105 of a tub provided with a liquid contents discharge passage, a valve in said passage and a valve operating lever connected with said valve, a heating element provided with a heating medium controlling member located 110 in the path of movement of said valve operating lever and adapted to be moved automatically into position to shut off the heating medium when said valve operating lever is operated to open said valve.

4. In a washing machine, the combination 115 of a tub provided with a liquid discharge pipe, a valve in said pipe, a valve operating lever connected with said valve, a gas burner adjacent said tub and a gas supply 120 pipe connected therewith having a shut-off valve, and an operating handle located in the path of movement of said liquid valve operating lever and adapted to be engaged thereby and moved into shut-off position in 125 the operation of said lever to open said liquid discharge valve.

5. In a washing machine, the combination

of a tub provided with a liquid discharge passage, a valve therefor, and a manually operable valve lever, a heating element having a supply passage, a valve, and a manually operable valve handle, the latter lying substantially in the path of movement of said discharge valve lever and adapted to

be engaged thereby in the movement of the same into open position to be moved into closed position.

10

In witness whereof, I hereunto subscribe my name this 5th day of November, A. D., 1919.

JOHN NEGRESCOU.
